US00D414562S

United States Patent [19]

Tajima

[11] Patent Number: Des. 414,562
[45] Date of Patent: ** Sep. 28, 1999

[54] PIPETTE TIP

[75] Inventor: **Hideji Tajima**, Inagi, Japan

[73] Assignee: **Precision System Science Co., Ltd.**,
Tokyo, Japan

[**] Term: **14 Years**

[21] Appl. No.: **29/080,409**

[22] Filed: **Dec. 8, 1997**

[51] LOC (6) Cl. **24-02**

[52] U.S. Cl. **D24/222**

[58] Field of Search **D24/222; 73/864.01,
73/864.03, 864.11, 864.14, 864.23, 864.25;
422/100**
